L. PAULERO,
CALKING TOOL,
APPLICATION FILED JAN. 16, 1918.

1,318,689.

Patented Oct. 14, 1919.

UNITED STATES PATENT OFFICE.

LOUIS PAULERO, OF PETERSBURG, VIRGINIA, ASSIGNOR TO AMERICAN ELECTRIC TOOL COMPANY, INCORPORATED, OF PETERSBURG, VIRGINIA, A CORPORATION OF VIRGINIA.

CALKING-TOOL.

1,318,689.

Specification of Letters Patent. Patented Oct. 14, 1919.

Application filed January 16, 1918. Serial No. 212,127.

To all whom it may concern:

Be it known that I, LOUIS PAULERO, a citizen of the United States, and a resident of Petersburg, in the county of Dinwiddie and State of Virginia, have invented a new and useful Improvement in Calking-Tools, of which the following is a specification.

My invention relates to improvements in calking tools, and it consists in the constructions, combinations and arrangements herein described and claimed.

An object of my invention is to provide a tool for calking the seams of vessels, so arranged as to be used in a mechanical hammer, and having provision for pressing the calking blade against the calking material with varying degrees of pressure.

Another object of the invention is to provide a tool as described, arranged to straddle the seam and having a funnel for guiding the calking material into the seam and beneath the tool.

Another object of the invention resides in the peculiar formation of the calking blade. Other objects and advantages will appear in the following specification, reference being had to the accompanying drawing in which:

Figure 1 is a section of the calking tool showing the blade pressed into the seam.

Fig. 2 is an end elevation of the tool.

Fig. 3 is an inverted plan view.

Fig. 4 is a cross section on the line 4—4 of Fig. 1.

Fig. 5 is a detail perspective view of the calking blade; and

Fig. 6 is a detail section hereinafter referred to.

The specific purpose of the invention is to provide a calking tool to be used in connection with a mechanically driven hammer, for driving oakum into the seams of a vessel in a rapid and effective manner. The calking tool is designed especially to be used in connection with the electric hammer described in my pending application filed Dec. 5, 1917, Serial No. 205,503, although obviously the calking tool is capable of use with any other mechanically driven hammer. The numerous advantages of a calking tool of this kind, together with the manner of operation thereof, will be fully brought out hereinafter.

Referring first to the construction of the calking tool, attention is directed to Fig. 1.

In carrying out the invention, I provide a

casing 1 which is round through the major portion, and terminates at the bottom in a square head 2 bifurcated in the center as at 3. The bifurcations are adapted to straddle the seam 4 between two planks 5 of the side 60 of a vessel.

The rounded portion of the casing 1 is knurled at 6 as shown in Fig. 2, in order to insure a firm grip of the workman's hand, and to prevent slipping of the tool in holding it against the planks 5. Internal threads 7 are provided at the top of the casing, and a cap 8 with a bore 9 screws into the threaded end of the casing. The rim of the cap 8 is also knurled as shown in Fig. 2. 70

Movable in the casing 1 and extending through a bore 10 in the bottom end adjacent to the bifurcations 3, is the shank 11 of the calking blade 12. The shank 11 projects a considerable distance out of the casing 1 at the top, and through the bore 9 of the screw cap 8. The end of the shank 11 is adapted to be fitted into the chuck of any of the well known types of mechanically driven hammers and as stated before, the 80 tool is preferably used in connection with my electric hammer. 75

Formed at one side of the casing 1 and on the inside of the casing, is a longitudinal groove 13. One end of a pin 14 moves in the groove 13 and prevents the shank 11 and consequently the calking blade 12 from turning with respect to the casing. The calking blade 12 is thus always held true in the center of the bifurcated head 2. A collar 15 is fixed 90 in place on the shank 11 by the pin 14 which projects through the collar and the shank as clearly shown in Fig. 1.

A novel means for removing the pin 14 without completely disassembling the calking tool, consists of the coaxial holes 16 and 17 in the upper portion of the casing 1. The hole 16 is smaller than the hole 17. The hole 17 is of the same diameter as that of the pin 14. Attention is directed to Fig. 6 95 100 whereon the manner of removing the pin is illustrated. The screw cap 8 is first partly unscrewed to bring the pin 14 in alignment with the hole 17. Ordinarily when the cap 8 is screwed down, the pin 14 is out of alignment with the hole 17, so that normally there is no danger of the accidental loss of the pin. 105

A rod 18 is thrust into the opening 16 against the end of the pin 14, whereupon the 110

rod is struck and the pin 14 is forced out of the hole 17. It will be readily understood from Fig. 1, that when the collar 15 is against the cap 8, in its screwed down position, the pin 14 will lie below the opening 17, so that the danger of the accidental removal of the pin just referred to, is entirely removed.

Disposed between the collar 15 and the lower end of the casing 1, is an expansion spring 19 which normally presses the collar 15 against the cap 8. The cap 8 provides a stop for the collar and consequently also provides a stop for the calking blade 12 so that the shank 11 may retract into the casing 1 no more than the prescribed distance. When the shank 11 is thus retracted in the casing 1, the calking blade 12 is about completely housed in the bifurcated end 2, the height of the blade being substantially the same as the distance between the closed end of the casing and the extremities of the bifurcations.

Attention is directed to the peculiar shape of the calking blade. This shape was adopted after considerable experimentation, and is adapted particularly well for use in driving oakum. The blade includes two regions, the upper one being shaped differently from the lower one. The sides of the upper region 20 are parallel as indicated in the visible portion of the blade as shown in Fig. 2. The lower region 21 gradually tapers to a rounded edge 22 at the extremity of the blade. The rear edge 23 of the blade is formed on a gradual curve, but the front edge of the blade lying in the zone 21 is formed first on an evolute and then on an involute curve. This front edge gradually widens from the lower edge 22 to the point of meeting with the tip 24 at the base of the upper zone 20.

This peculiar formation of the calking blade 12 has, what might be termed, an initiating action on oakum. This will presently be more fully apparent, but it will be understood from Fig. 1 that as the oakum O is fed into the seam 4 and the calking tool moves along over the oakum, the double curved front edge 21 with the thin portion at the bottom and broad portion at the top, gradually presses the oakum into the seam, and when the edge 22 moves over the oakum, it will be found that the oakum will have been uniformly pressed into the seam whereupon the striking of the hammer on the tool will drive the oakum so securely into the seam that it will not come out.

A funnel 25 guides the oakum to the calking blade. The funnel is substantially rectangular in shape at the front as shown in Fig. 2, and includes the arms 26 which embrace the square head 2 and are secured thereon by the screws 27. The guide 25 has an opening 28 at the base of the upper por-

tion of the funnel to accommodate the tip 24 of the calking blade. The bottom edge of the guide is of course open, and the base of the funnel adjacent to the opening 28 is constricted in width to substantially that of the seam 4. The purpose of this arrangement is obvious. The bulk of the oakum is considerable, and the purpose of the formation of the guide 25, is to move over the oakum, press it down and inwardly, whereupon the driving action of the calking blade as just described, commences.

The operation and advantages of the calking tool are as follows. Variable pressures on the calking blade 12 are possible through the agency of the spring 19. The operator may bear on the hammer in the chuck of which the shank 11 is inserted, as hard as may be desired, and the result is that the spring 19 will compress accordingly and the blade 12 will be thrust into the seam 4 a corresponding distance.

In practice, the operator takes a roll of oakum which usually comes in the shape of a rope, and hangs it over the left arm. The end of the oakum is then put into the seam, and the calking tool is set over the oakum and the seam with the open end of the funnel or guide nearest the operator. On starting the hammer, the calking tool is simply drawn along lengthwise of the seam and over the oakum, which is thus hammered into the seam in the manner hereinbefore fully explained. If the operator desires to drive the oakum into the very base of the seam as is done on the first operation, he bears correspondingly hard on the hammer. Whether or not other portions of oakum are hammered on top of the previously placed oakum, depends altogether on the size of the seam and of the oakum itself. Such conditions occur in every day practice and of course are readily overcome by the user of the tool.

Heretofore the seams in wooden vessels were calked with hand tools. The object of the invention is primarily to expedite the calking operation, since the use of the hand tools involves a long and tedious process. Incidentally, the calking tool comprising the blade 12 and shank 11 may be used as a hand tool if it be so desired, it being understood that the peculiar formation of the calking blade illustrated in Fig. 5 has equally peculiar and effective advantages. The tool is preferably made of properly hardened tool steel so that it may withstand the incessant blows of the hammer.

As formerly pointed out, the open bottom of the oakum guide 25 enables the lifting of the tool from the seam without catching on the oakum. The funnel shaped formation of the guide causes the gathering of the oakum string and crowding thereof at the constricted base, where it is crowded down

into the seam and quickly driven into place by the blade 12.

While the construction and arrangement of the calking tool is that of a generally preferred form, obviously modifications and changes may be made without departing from the spirit of the invention or the scope of the claims.

I claim:

10 1. In a calking tool, a shank adapted to be inserted into the chuck of a mechanically driven hammer, and a calking blade on the shank adapted to operate against calking material in a seam, said blade including an edge having evolute and involute curves for gradually compressing said material for action thereon by the driving edge of the blade.

2. A calking tool including a shank, and 20 an integral blade having an upper region with parallel sides and a lower region with sides tapering to the driving edge, the front edge of the blade in the lower region being formed on a double curve to gradually introduce the calking material to a seam and to the driving edge.

3. A calking tool including a shank, and 30 an integral blade having an upper region with parallel sides extending forwardly into a tip, and a lower region with sides tapering to a driving edge, the front edge of the lower region being formed on a double curve gradually widening to the tip.

4. In a calking tool, a casing having a 35 bifurcated end open on the bottom for straddling a seam, a shank movable in the casing with an integral calking blade occupying the space between the bifurcations and adapted to drive calking material into 40 the seam, and a funnel shaped guide attached to the bifurcations for gathering and crowding the calking material into the seam in advance of said blade, said guide being open on the bottom to permit lifting of the 45 tool from the seam without catching on the calking material.

5. In a calking tool, a casing having a 50 groove, and coaxial holes in the walls of the casing, a cap closing the casing, a shank occupying the casing and movable in the cap, a collar on the shank, a spring pressing the collar against the cap, and a pin holding the collar on the shank with a projecting end occupying the groove to prevent the shank

from turning, said pin being in normal dis- 55 alinement with said holes but adapted to be brought into alinement for removal by partly removing said cap.

6. A calking tool including a bifurcated head arranged to slide over the boards and 60 straddle the seam between the boards, a guide open at the bottom to the seam, attached to the front of the head extending the supporting base of the tool, and consisting of forwardly flaring sides and top 65 to constitute a rearwardly tapering tunnel, adapted to gather the calking material at the front and compress it into the seam toward the rear, and a reciprocating calking iron vertically movable across the rear 70 of the guide for driving the calking material into the seam.

7. A manually directed calking tool including a blade with a shank adapted to be fixed in the chuck of a mechanically driven 75 hammer, the calking tool being wieldable with said hammer, a casing receiving said shank and having a bifurcated end partly embracing said blade and adapted to straddle the seam, resilient means coöperating 80 with the shank within said casing normally holding said blade within said bifurcated portion, and an attached guide extending the supporting base of the tool, with a passage in continuation of the space between the 85 bifurcation, said passage being open to the seam throughout its length and being rearwardly tapered to initially compress calking material into the seam beneath said blade.

8. A calking tool comprising a casing with a bifurcated head for straddling a seam, an attached oakum guide bridging the seam, said guide having flaring sides and a flaring top cut short of the sides at the rear 95 to leave a space, and a calking blade reciprocatively mounted in the casing, having a tip moving within the sides of the guide and in said space at the rear.

9. The combination in a calking tool, of 100 an oakum compressing guide open on the bottom and having flaring side and top walls to provide a flaring mouth and a constricted outlet, and a calking blade having a tip vertically movable across said outlet to introduce the compressed oakum into a seam.

LOUIS PAULERO.
